SPRING ARC SUPPORT

Raymond P. Cover, Springdale, Conn.

Application July 27, 1948, Serial No. 40,920

6 Claims. (Cl. 267—48)

1

This invention relates to a spring arc support adapted to reinforce a laminated leaf spring such as the standard semi-elliptical type well known in the art. Devices of this class have been known for many years, and there are a great many patents showing various constructions suggested by prior workers in this field. So far as I know, however, no truly successful construction has ever been contributed to the art, although I have achieved a considerable degree of success with a device set forth in my earlier application for Patent No. 635,848 filed December 19, 1945, now Pat. No. 2,525,065 dated October 10, 1950.

It is the object of this invention to contribute a spring arc support that will function effectively and with a minimum of friction to reinforce and maintain in an effectively operating position the leaves of a laminated leaf spring.

As a feature of my invention whereby the results thereof are obtained, I utilize a spring-like bar having one end thereof applied directly against substantially the shortest leaf of the spring, the other end of the spring-like bar being applied to the surface of the substantially longest leaf of the laminated leaf spring. Through this arrangement, preferably a considerable length of the spring-like bar at one end thereof is actually supported in position by the entire laminated leaf spring so as to apply through the remainder of the bar a considerable pressure that is effectively utilized to bolster and support the longest leaf of the laminated leaf spring.

As a more particular feature of my invention, the spring-like bar that is utilized as my spring arc support is separated from the spring that it reinforces except where it is applied at its ends to the leaves of the spring. Through this arrangement, friction is effectively eliminated and my spring arc support operates most efficiently.

As a further feature of the invention, I utilize a shim applied to the leaf spring itself for maintaining my spring arc support against linear movement relatively to the leaf spring.

As a still further feature of the invention, I utilize a novel means for securing one end of my spring arc support to the leaf spring with a portion thereof operating against the eye of the spring for preventing movement of the spring-like bar relatively to the spring.

I have thus outlined rather broadly the more important features of my invention in order that the detailed description thereof that follows may be better understood, and in order that my contribution to the art may be better appre-

2

ciated. There are, of course, additional features of my invention that will be described herein-after and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is an elevation showing approximately one-half of a conventional semi-elliptical spring reinforced by the spring arc support of my invention. Figs. 2 and 3 are sections taken respectively along lines 2—2 and 3—3 of Fig. 1. Fig. 4 shows rivets for securing a plate to the flat spring-like bar constituting my spring arc support. Fig. 5 shows a modification of the means utilized for securing one end of my spring arc support to the longest leaf of the semi-elliptical spring. Fig. 6 is a section taken along lines 6—6 of Fig. 5. Fig. 7 is a perspective view of a U-bolt utilized as part of the structure of Figs. 5 and 6.

Referring now more particularly to the drawings, reference numeral 10 indicates generally the main frame of an automobile or the like having downwardly depending ears 11 for supporting a bolt 12 that carries the eye 13 of a laminated leaf spring L, the said eye 13 being an integral part of the upper and longest leaf 14 of the said spring. The central portion of the laminated leaf spring L is secured through suitable U-bolts 15 to a part 16 carried by an axle 17, all as is quite conventional in this art. It is the general purpose of my invention as already set forth, to apply to the spring L a spring arc support for holding it arched as in Fig. 1, my device being especially useful where the spring has been overloaded or through age has lost some of its resilience.

The spring arc support of my invention comprises a spring-like bar 18 having a substantial linearly extending surface 19 applied to the underside of what may be the shortest leaf 20 of the several leaves comprising the spring L. For holding the portion 19 of the bar 18 against leaf 20 I utilize a U-bolt 21 traversing at its ends a plate 22 that may be welded to the underside of the bar 18 as shown at 23. If desired, and as shown in Fig. 4, the plate 22 may be riveted through rivets 24 to the bar 18. Regardless of the manner in which the plate 22 is secured to

the bar 18, the tightening of nuts 25 on the ends of the U-bolt 21 will secure the surface 19 against the lower leaf 20 as is well illustrated in Fig. 1.

That portion of the spring-like bar 18 constituting my spring arc support that is to the left of the surface portion 19 is preferably so bent as to be spaced from the several leaves of the spring L except at its very extreme left end. Thus, at its extreme left end the spring arc support 18 has a portion 26 that is applied directly to the underside, preferably of the longest leaf 14 of the leaf spring L. Because of the particular arrangement, it is the heaviest part of the spring L formed by assembly of all its leaves that supports the spring arc support 18 in position for reinforcing at the portion 26 the longest leaf 14 of the spring. In other words, all the reinforcing stresses are applied through the spring-like bar 18 to substantially the central portion of the spring L where substantially all the leaf laminations are secured to one another.

The left end of the spring arc support 18 may be secured to the leaf 14 by a stabilizer 27 that is applied initially with its portions 27a as shown in dash and dotted lines in Fig. 3. Once the stabilizer is so applied, the portions 27a will be bent over into the full line position illustrated in Figs. 1 and 3.

For preventing endwise movement of the spring arc support to the left in Fig. 1, I may utilize a shim 28 formed of metal and inserted between the leaves of the spring. The ends of the shim 28 extend outwardly, as best illustrated in Fig. 2, to obstruct movement of the U-bolt 21 and the spring arc support to the left in Fig. 1.

In Figs. 5, 6, and 7, I show a U-bolt 30 that is used in the place of stabilizer 27 and the shim 28. Thus, U-bolt 30 is adapted to have its screw-threaded ends 31 traverse holes 32 in a plate 33 that is welded or otherwise secured to the left end of the spring arc support 18. Through nuts 34 the U-bolt 30 is applied to the leaf 14 of the leaf spring L for holding the surface 26 at the left end of the spring arc support against the underside of leaf 14 and thereby, I very effectively secure the spring arc support 18 relatively to the leaf 14. A lug 35 formed integrally with the U-bolt 30 extends to the left therefrom as shown in Fig. 5, whereby to impinge against the eye 13 of the leaf spring L. It is quite obvious that with this relationship of the parts, the lug 35 will prevent any movement to the left of the spring arc support 18. Thereby, the lug 35 will replace the shim 28 rather effectively, while the U-bolt 30 will function more efficiently than does the stabilizer 27.

I believe that the considerable merits of my invention and my contribution to the art will now be apparent to those skilled in the art.

I now claim:

1. A spring arc support for supporting and reinforcing a laminated leaf spring of the type having a series of leaves with the longest leaf terminating in an eye comprising a spring-like bar having one end section thereof formed with a substantial linearly extending surface applied directly against a similarly extending surface of substantially the shortest leaf of the laminated spring where substantially all the leaves of said spring are assembled, clamping means at substantially the beginning of said end section clamping said spring arc support to said laminated leaf spring with the said surface of said end section applied against said shortest leaf, the other end of the spring-like bar having a sur-

face applied to the longest leaf of said laminated spring and extending substantially to the eye thereof, the bar portion between said surfaces being spaced from said spring, and means additional to said clamping means for preventing said bar from sliding in the direction of the eye of said longest leaf.

2. A spring arc support for supporting and reinforcing a curved laminated leaf spring of the type having a series of leaves with the longest leaf terminating in an eye comprising a spring-like bar having one end section thereof formed with a substantial linearly extending surface applied directly against a similarly extending surface of substantially the shortest leaf of the spring, said spring arc support curving generally in the same direction as said longest leaf, clamping means at substantially the beginning of said end section clamping said spring arc support to said laminated leaf spring with the said surface of said end section applied against said shortest leaf so that said spring-like bar is in effect a part of said laminated spring, the other end of the spring-like bar having a surface applied to the longest leaf of said laminated spring and extending adjacent to the eye thereof whereby the stress applied to said longest leaf is transmitted to said spring arc support and in turn to said entire leaf spring at that portion thereof where all the leaves of the leaf spring are assembled, the bar portion between its said surfaces being spaced from the intervening leaves of said spring.

3. A spring arc support for supporting and reinforcing a laminated leaf spring of the type having a series of leaves graduated in length with the longest leaf terminating in an eye comprising a spring-like bar having one end section thereof formed with a substantial linearly extending surface applied directly against a similarly extending surface of substantially the shortest leaf of the spring, means at substantially the beginning of said end section clamping said spring arc support to said laminated leaf spring with the said surface of said end section applied against said shortest leaf, a second linear section at the other end of the spring-like bar having a substantial linearly extending surface applied to the longest leaf of said laminated spring and extending substantially to the eye thereof, the bar portion between said sections being spaced from said spring, means at the beginning of said second section securing said bar relatively to said longest leaf, and a part integral with said means to abut the eye of the spring for preventing said bar from sliding toward the eye of said laminated spring.

4. A spring arc support for supporting and reinforcing a curved laminated leaf spring of the type having a series of leaves graduated in length with the longest leaf terminating in an eye, comprising a spring-like bar having one end section thereof formed with a linearly extending surface applied directly against a linearly extending surface of substantially the shortest leaf of the spring where substantially all the leaves of said spring are assembled, said spring arc support curving generally in the same direction as said longest leaf, clamping means clamping said section of said spring arc support directly against said laminated leaf spring and applied to said leaf, the other end of the spring-like bar having a surface applied to the longest leaf of said laminated spring and extending adjacent the eye thereof, whereby the stress applied to said longest leaf is transmitted to said spring arc support and in turn to said entire leaf spring at the part of

said leaf spring where all its leaves are assembled. 5. A spring arc support for supporting and reinforcing a laminated leaf spring of the type having a series of leaves graduated in length with the longest leaf terminating in an eye, comprising a spring-like bar having one end surface applied directly against a surface of substantially the shortest leaf of the spring where substantially all the leaves of said spring are assembled, a U-bolt securing said end of said spring arc support to said laminated leaf spring with the said end applied against said shortest leaf, the other end of the spring-like bar having a surface applied to the longest leaf of said laminated spring and extending substantially to the eye thereof, the bar portion between said ends being spaced from said leaf spring, a second U-bolt at the said other end of said bar securing said bar relatively to said longest leaf, and means integral with said second U-bolt for preventing said bar from sliding in the direction of the eye of said spring.

6. A spring arc support for supporting and reinforcing a laminated leaf spring of the type having a series of leaves graduated in length with the longest leaf terminating in an eye, comprising a spring-like bar having one end applied directly against a surface of substantially the

shortest leaf of the spring where substantially all the leaves of said spring are assembled, clamping means securing said end of said spring arc support to said laminated leaf spring with the said end applied against said shortest leaf, the other end of the spring-like bar being applied to the longest leaf of said laminated spring, the bar portion between said ends being spaced from said spring, a clamping means at the said other end of said bar securing said bar relatively to said longest leaf, and means integral with said second clamping means adapted to abut the eye of the spring for preventing said bar from sliding in the direction of the eye of said laminated spring.
